His Attorney.

UNITED STATES PATENT OFFICE

WILLIAM DALTON, OF GLENVILLE, NEW YORK

RAILROAD-TRACK STRUCTURE

Application filed April 11, 1929. Serial No. 354,390.

The present invention relates to railroad track structures and especially to an improved construction and arrangement for clamping or fastening a track rail to a tie plate or other rail supporting member. The invention may be used in connection with either wooden ties or metal ties. It is well adapted for use with a metal tie such as that disclosed in my Patent No. 1,657,241, dated January 24, 1928.

An object of my invention is to provide an improved structure wherein the rail fastening means or clamping means comprises only a single member which when positioned is wedged into place so it cannot come out whereby it forms a most efficient fastening, the fastening member, at the same time, being simple in structure so that it may be manufactured at low cost.

For a consideration of what I believe to be novel and my invention, attention is directed to the following specification and the claims appended thereto.

In the drawing, Fig. 1 is a transverse sectional view of a structure embodying my invention; Fig. 2 is a side view of the clamp shown in Fig. 1; Fig. 3 is a perspective view of the clamp; Fig. 4 is a view similar to Fig. 1 showing a modification, and Fig. 5 is a side view of the clamp shown in Fig. 4.

Referring to the drawing, 1 indicates a railroad track tie and 2 indicates a tie plate supported thereon, the tie plate being provided with spaced openings 3 to receive a fastener or clamp for attaching a rail to the tie. The tie plate may be one of standard structure and preferably on its thicker side it is provided with a bottom recess 4 of a depth such that the same size fastener or clamp will fit both openings 3. A clearance is required beneath the tie plate to receive the lower end of the fastener or clamp. In the case of a metal tie, this may be made inherent in the structure as in the tie shown in my above referred to patent. In the case of a wooden tie, the clearance may be provided by forming holes in the tie as is indicated at 5 in Figs. 1 and 4, 6 being a drain hole for discharging water. 7 indicates a rail supported on the tie plate.

Referring now to Figs. 1 to 3, the form of clamp here shown comprises a metal block having a concave inner face 8 formed about the point *a* as a center and provided at about its central portion with a transverse circular ridge 9 formed about a center *b*. Ridge 9 forms a fulcrum for the clamp when it is put into place. The outer face 10 of the clamp is convex and is formed about a center *c* located above center *a*. The radius of face 10 is greater than the radius of face 8 so that there is formed a wedge shaped toe 11. The upper edge of face 10 terminates in a ridge 12 formed about a center *d*, center *d* being located below center *b* as is shown in Fig. 2. Just above ridge 12 is a shoulder 13 which forms a stop for limiting downward movement of the clamp. Above shoulder 13 is a second shoulder 14 which may be used for removing the clamp by the use of a pinch bar. This may be done by placing the bar under shoulder 14 and prying up on the shoulder. The inner upper end of the clamp is in the form of a toe 15 which stands over the edge of the base flange of the rail to hold the rail on the tie.

When the clamp is to be inserted in an opening, it is placed in the opening as shown at the right hand side of Fig. 1, the ridge 9 resting against the inner face of the opening and the ridge 12 engaging the upper outer corner of the opening. The clamp is then driven down with a suitable tool to bring it to the position shown at the left hand side of Fig. 1. In being driven down, the clamp turns on the ridge 9 as a fulcrum and ridge 12 is moved from a position where the horizontal plane of its center is above the horizontal plane of the center of ridge 9 to a position where the horizontal plane of its center is below the horizontal plane of the center of ridge 9. The clamp then engages the tie plate at three points indicated at *x*, *y* and *z* at the left of Fig. 1, the clamp being wedged into position with the point *x* below the point *y*. The clamp is thus firmly held and any pressure applied upward to the under side of toe 15 by the rail flange will tend to wedge the clamp still tighter. The clamp may be removed by prying under shoulder 14.

14 with a pinch bar or other suitable tool. I may, if found desirable, give a small amount of flexibility to the clamp in a transverse direction by providing saw cuts therein as is indicated at 16.

5 In the Fig. 1 construction, it will be seen that there is a space 17 left between the top of the base flange of the rail and the under surface of toe 15, such a space being desirable in some instances for known reasons. 10 This space may be made of any desired width by shaping the clamp. In this form of the invention the clamp is held entirely in the tie plate.

15 When it is desired to fasten the rail down tight on the tie plate, I may use a construction as shown in Figs. 4 and 5. This construction is generally similar to that of Figs. 1 to 3 except that the ridge 9 is omitted, and the same reference numerals with the exponent "a" added have been applied to corresponding parts. The clamp engages the rail and tie plate at the three points *u*, *v* and *w*, the horizontal plane of the point *u* being 20 below the horizontal plane of the center of concave surface 8^a. With this arrangement it will be seen that the base flange of the tie is clamped down tightly on the tie plate. At the right hand side of Fig. 4 the clamp is 25 shown as having been placed in the opening ready to be driven to position, the concave inner surface being in engagement with the top corner of the base flange of the rail and with the lower inner corner of the opening. 30 When driven down, the clamp turns on these two corners and moves to the position shown at the left hand side of Fig. 4. In this construction, saw cuts, corresponding to the saw cuts 16 of Figs. 1 to 3, are not provided. It 35 will be understood, however, that they may be provided if found desirable.

40 In connection with both the constructions illustrated, it will be seen that the engaging ridge 12 or 12^a lies between the other two lines of engagement and in a position such that the clamp is held in position after the manner of a toggle that is forced past the horizontal line connecting the center of its two arms. This insures a tight wedging into place of the 45 clamp and makes impossible its coming out by upward pressure applied by the rail flange against the under side of toe 15 or 15^a.

50 What I claim as new and desire to secure by Letters Patent of the United States is:

55 1. The combination with a tie plate having an opening, of a clamp adapted for insertion into said opening to fasten a rail in position, said clamp having a concave inner face and a convex outer face provided with a transverse 60 ridge, said concave inner face receiving the adjacent edges of the opening and the rail flange, and said ridge wedging against the outer face of said opening on a line below its top edge.

65 2. The combination with a tie plate having

an opening, of a clamp adapted for insertion into said opening to fasten a rail in position, 70 said clamp having a concave inner face and a convex outer face provided with a transverse ridge, said convex face being formed with a radius greater than the radius of the inner face whereby the clamp is wedge shaped, said concave inner face receiving the adjacent edges of the opening and the rail flange, and said ridge wedging against the outer face of 75 said opening on a line below its top edge.

3. A clamp for fastening a rail to a tie plate comprising a wedge shaped block having a concave inner face and a convex outer face, 80 said convex outer face having a transverse curved ridge and a transverse shoulder above the ridge, the radius of curvature of the outer convex face being greater than the radius of curvature of the inner concave face.

4. A clamp for fastening a rail to a tie plate comprising a wedge shaped block having a concave inner face and a convex outer face, 85 said faces being provided with transverse ridges, the ridge on the outer face being lower than the ridge on the inner face.

5. A clamp for fastening a rail to a tie plate comprising a wedge shaped block having a concave inner face and a convex outer face, 90 said outer face being provided with a transverse ridge, and said block being provided with a narrow transversely extending slot.

6. The combination with a tie plate having an opening, of a clamp adapted for insertion 100 into said opening to fasten a rail in position, said clamp being provided with a concave inner face having a transverse ridge and a convex outer face having a transverse ridge, said ridges being so located relatively to each other 105 that when the clamp is inserted in said opening, said outer ridge engages the outer face of the opening along a line lower than that at which the inner ridge engages the inner face of the opening.

7. The combination with a tie plate having an opening, of a clamp adapted for insertion 110 into said opening to fasten a rail in position, said clamp being provided with a concave inner face and a convex outer face having a transverse ridge, 115 said ridge being so located that when the clamp is inserted in said opening it engages the outer face of the opening along a line below the center of curvature of said concave inner face.

120 WILLIAM DALTON.
